LOCKING BOX

Thomas H. Gagen, Sandusky, Ohio, assignor to
 The Hinde & Dauch Paper Company, Sandusky,
 Ohio, a corporation of Ohio

Application May 3, 1937, Serial No. 140,404

2 Claims. (Cl. 229—16)

My invention relates to paper boxes, using the term "paper" in a broad sense, and is particularly directed to an interlocking fastening which will not only be strong and snug-fitting without 5 tape or adhesive, but also be easy to fasten and not accidentally become unfastened; wherein the fastening elements per se coact with other end elements to increase the end thickness and wherein the disposition of parts contributes to 10 economy in the use of material.

The phase of my invention which is mentioned above is also of valuable effect in connection with another phase of my invention, namely a box made from a single blank and having two substantially complete shells, one entirely enclosing or almost entirely enclosing the other, both parts held assembled and closed by a single lock. Part of the second phase of the invention is a blank for the purpose which permits an economical cutting layout, minimizing waste of sheet material. Furthermore, my invention aims to provide a box of this sort in which the assembly operations are reduced to a minimum and in which the amount of permanent corner fastening required by tape sealing or by corner stitching is reduced to a requirement of one place only, while the box still retains all the characteristics of a double shell box except that the parts do not slide one within the other.

To the accomplishment of the foregoing and related ends, said invention, then, consists of the means hereinafter fully described and particularly pointed out in the claims.

The annexed drawings and the following description set forth in detail certain structure embodying the invention, such disclosed means constituting, however, but one of various structural forms in which the principle of the invention may be used.

In the accompanying drawings:

Fig. 1 shows the flat blank from which one form of my improved box is made;

Fig. 2 is a perspective of the box made from the blank of Fig. 1, shown closed in solid lines;

Fig. 3 is a perspective of the box set up and partly open;

Fig. 4 is a larger scale elevation, partly in section, of the inner front, taken on the plane 4—4 of Fig. 5, in the direction of the arrows;

Fig. 5 is a larger scale transverse vertical section on the plane 5—5 of Figs. 2 and 6, in the direction of the arrows;

Fig. 6 is a larger scale longitudinal vertical section on the plane 6—6 of Figs. 2 and 5, in the direction of the arrows;

Fig. 7 shows the flat blank for another form of my improved box;

Fig. 8 is a perspective of a box set up from the blank of Fig. 7, with one end open and the other closed, and also showing a slight modification 5 at the closed end;

Fig. 9 is a vertical section on the plane 9—9 of Fig. 10 with some elements in elevation and looking in the direction of the arrows;

Fig. 10 is a larger scale partial plan, with some 10 elements in elevation, taken on the horizontal plane 10—10 of Fig. 9, looking upward.

It will be apparent that my improved box, in all of its forms, includes a locking device consisting of a single tongue which so co-acts with 15 the inner edges of a divided tuck flap as to be pinched by those edges, the edges themselves being specially formed for the purpose, and thereby constituting an interlock between the tuck flap and the tongue.

The opposing relations and the relative planes in which the divided tuck flap and the tongue lie varies according to the shape and nature of the box to which the locking device is applied, preferred embodiments being herein illustrated and 25 more fully described in conjunction with the particular boxes to which applied.

In the form illustrated in Figs. 1 to 6 inclusive, I have applied this locking device to a box which is of the double wall variety, and which by my 30 lock and the addition of a fastener at only one of the dihedral corners, is made up into an assembled box having four walls of double thickness and two of single thickness. The shape of this particular box also gives rise to economies 35 of cutting blanks from sheet material on account of the peculiar shape of the blank. It will be observed that this double walled box is formed from a unitary blank.

The blank will of course vary in the proportions of its parts according to the desired finished dimensions of the box. The specific blank illustrated in Fig. 1 and made up into the box shown in Figs. 2 to 6 inclusive, is shallow, rectangular in plan, slightly larger from front to rear than 45 from side to side.

Such terms as front, rear, top, bottom, sides and ends, are used in the specification and in such claims as read upon this embodiment with reference to the relations of parts in Fig. 3 and 50 50 are intended for description and identification, but not as limitations.

The blank, Fig. 1, is L-shaped in general outline, thus adapting itself to economical lay-out 55 of the sheet, as will be understood by box mak-

ers. This blank comprises areas separated by creases for bending, such creases being indicated in Fig. 1 by dotted lines, and full cuts in that figure by solid lines. For convenience in all the drawings the panels of the blank are designated by letters, while lines and edges are designated by numerals.

The outer covering of the assembled box is formed from the top A, back B, bottom C and front D, while the inner shell of the box consists of left side E, inner back F, right side G, tuck flap H', H², (generally mentioned hereafter as H), tongue J', J², (generally mentioned hereafter as J), inner bottom K', K², K³, (generally mentioned hereafter as K), and inner top L', L², L³, (generally mentioned hereafter as L). The two parts of the tuck flap H are each inwardly terminated by curved edges 2 which widen out toward the base of the flap, forming corners 3 which bind the edges of the tongue J as is best seen in Figs. 2 and 10. The tongue J is rooted to the outer back D at the crease 4 and is itself transversely creased at 5. In the blank the tongue is directly opposite the opening between the parts of the tuck flap H, and the tongue width is substantially equal to the distance 3-3, so that in the assembled box the tongue is entered into the space between the corner 3, 3 at the root of the tuck flap H, and 30 there held.

In the blank there is a full cut along the ultimate left edge 8 of the bottom C, separating it from the inner bottom panel K'. Thus the only attachment of the upper part of the blank to the lower part is along the bending crease 9 between D and E.

Each of the panels E, F and G carries wings K', L', and so on, the adjacent edges of which are cut diagonally as at 10, 11, 12 and 13, and 40 20, 21, 22 and 23 so as to abut and not overlap when the inner portion of the box is set up, as shown in Fig. 3. The proportions of the wings L', L² and L³ are such that when assembled a central opening is left by edges 14, 15 and 16 45 of these parts, which opening is of the size and shape of the tongue J, as is apparent in Fig. 3. Thus, when the box is completely filled and is closed, the tongue forms another element of the inner top, making the latter complete. Although 50 not so shown in the present embodiment, it would be easily possible, if desirable, to so shape the elements of the inner bottom K as not to leave any corresponding space.

When set up, the edge 30 of the right side G 55 abuts the edge 31 of the outer front D and the two are fastened by adhesive tape 32 or other suitable means. Thus, in order to fill the box, the inner top wings L', L², L³ are raised, although this raised position is not shown in the drawings.

60 Assuming the box to be assembled as in Fig. 3, filled (although no filling is shown in that figure), and the inner top L laid down flat, the tongue J will be bent further back along the line 4 than the position shown, and the tuck H inserted behind D and in front of the edges 35 and 36. When the tuck flap H is about half way down, the outer tongue portion J² will be inserted between the corners 3, 3, which can be accomplished by reason of the bend in the 70 tongue, and as the tuck flap H is moved down to final seating, the tongue is moved in, so that in the closed box it occupies the dotted line position J of Fig. 2, thus filling the vacant space in the inner top, and by the binding action of the 75 corners 3 prevents lifting of the lid A.

Thus the box is closed with double thickness throughout substantially its entire area except at the ends G and E, and the outer lid is fastened down by a tongue which is difficult to extract.

The application of my lock to another form of box is shown in Figs. 7 to 10 inclusive, where the tongue and flap combination is employed on each end of the box, the box being otherwise an ordinary single thickness container which may 10 be either open-ended with front and bottom permanently closed by a tape 61, or may be formed without a tape, as desired. Whether or not a tape is required depends upon such factors as the size of the box, the weight of load it is designed to carry and the roughness of usage to which it may be subjected.

In this form the blank comprises creases and edges defining front M, top N, back O, bottom P, inner end flaps Q and Q', outer ends R, tuck 20 flaps S' and S², (collectively designated as S), and locking tongues generally designated as T, rooted at the crease 69 but divided into two parts T' and T² by a transverse crease 75. The parts may conveniently be so proportioned that 25 the tongue T fills the space between flaps Q and Q' when the box is closed and fastened.

It will be apparent that the tuck flaps S and tongues T are analogous to the corresponding elements H and J of Figs. 1 to 6 inclusive, 30 although the general construction of the box brings them into conjunction from differently disposed panels of the blank. The tuck flap S is separated into its parts S' and S² by inner edges 62, which form corners 63 with the end panel R, 35 obviously similar to the corresponding parts 2 and 3 of Figs. 1 to 6.

Thus, to form and close the box, the parts are bent along the appropriate creases into the relationship shown in Fig. 8. If desired, a tape 61 40 connects the abutting edges 65 and 66 of the front M and bottom P respectively, as shown in the left half of Fig. 8.

To close the box the flaps Q, Q' are swung inwardly as shown in Fig. 9, the end R is turned 45 up and the tuck flap S inserted above the upper edges 76, 61 of Q and Q', and beneath the top N. Before the tuck flap S is seated, the portion T₂ of the tongue T will be started into the space 63-63, the bend line 65 allowing the necessary 50 flexibility for the purpose. As the tuck flap S is moved fully inward the tongue T is further inserted so that when the box is closed the end presents a smooth appearance similar to the front of the box of Fig. 2. However, in the 55 present form the tongue T lies vertically as shown in Fig. 9. The box is thus locked in all directions, because the edges 67 and 76 bear against S₂ and S', respectively, preventing the top N from lifting, and the edge 68 bears against the bottom P, preventing the bottom from rising. The tongue T locks in the corners 63, as shown in Fig. 10, preventing S from sliding out.

The tightness of the lock is to some extent dependent upon the accuracy of fit of the parts 65 and the stiffness of the material. Thus, if it is desired that the box shall not be too difficult to open, the tongue T can be made slightly narrower so as not to fit too snugly in the space 63-63, and other clearances can correspondingly be left 70 somewhat free. On the other hand, by cutting all parts to close-fitting dimensions, the box can be locked so tightly as to require breaking or cutting along some of the front lines, such as the fold 69 at the root of the tongue T or the 75

fold 78 at the root of the tuck flap S, before the box can be opened.

From the foregoing it will be seen that I have invented a lock adapted to various forms of boxes, which firmly secures the parts of the boxes in their closed relation, and also firmly secures itself against unlocking, and also have invented various forms of boxes in which full advantage may be taken of the tight and firm character of my improved lock. My invention also offers the advantages of simplicity and economy of material, and readiness of assembly.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. A box of the character described comprising in combination interior and exterior casings, the interior casing comprising a unitary succession of walls separated by bending creases, wings attached to opposite sides of said walls adapted to be folded at right angles thereto in the finished box, the wings on each side of said walls comprising partial surfaces with edges angular

in the blank and abutting in the assembly and having a combined area substantially equal to the area of a contiguous wall of the outer casing, the exterior casing comprising a front wall attached in the blank to an end of said successive walls, and having a bottom, a back, and a top successively attached thereto, and locking in alignment on the outward edges of said front and top respectively.

2. A double shell box comprising in combination inner top and bottom elements hinged to box side walls, a top, bottom, front and back, a locking tongue hinged to said front, a tuck flap hinged to said top, the front being hinged to one said side wall, and said top, bottom, front and back being adapted to overlie said inner top and bottom, the inner top and bottom being formed in segments equal in area to the outer top and bottom, edges on said top wall segments defining a space, when the box is closed, substantially equal to the area of said locking tongue, and said locking tongue lying, when the box is locked, substantially in the plane of said inner top and said tuck flap lying, when the box is locked, behind and in a plane contiguous to the outer front.

THOS. H. GAGEN.
